No. 717,918.

PATENTED JAN. 6, 1903.

C. P. PHILBRICK.
ELECTRICAL REGULATOR.
APPLIATION FILED JUNE 13, 1902.

NO MODEL.

UNITED STATES PATENT OFFICE.

CHARLES PIERSON PHILBRICK, OF WYMORE, NEBRASKA, ASSIGNOR OF
ONE-HALF TO JOHN A. REULING, OF WYMORE, NEBRASKA.

ELECTRICAL REGULATOR.

SPECIFICATION forming part of Letters Patent No. 717,918, dated January 6, 1903.

Application filed June 13, 1902. Serial No. 111,495. (No model.)

To all whom it may concern:

Be it known that I, CHARLES PIERSON PHILBRICK, a citizen of the United States, and a resident of Wymore, in the county of Gage and State of Nebraska, have invented a new and Improved Electrical Regulator, of which the following is a full, clear, and exact description.

My invention relates to pressure-controlled electric mechanism for regulating the flow of fuel to a furnace located beneath a boiler.

Reference is to be had to the accompanying drawing, forming a part of this specification, in which the figure represents my invention as applied to a steam-boiler energized by liquid fuel.

The boiler 1 is provided with a pressure-motor consisting of a casing 2, provided with a diaphragm 3, upon which diaphragm is mounted a movable plunger 4, provided with a point 5, the arrangement being such that variations in the pressure of the boiler produce corresponding variations in the position of the point 5. The outer end of the casing 2 is rigidly secured to the frame 6, and through this frame the plunger 4 is free to move longitudinally when actuated by the diaphragm. Upon a pivot 7, supported by a bracket 9, is mounted a bell-crank lever 8, connected by a spring 10 with the frame 6. An adjusting-screw 11, provided with a clamping-nut 12, forms the intermediate connection between the spring 10 and the bell-crank lever. Upon the free end of the bell-crank lever is a somewhat similar adjusting-screw 13, provided with a thumb-nut 14. The screw 13 engages an electrode 15, having the form of a leaf-spring and pivoted at 16 upon an insulating-bracket 17, secured by means of a screw 18 upon the rod 19 of the frame 6. This insulating-bracket 17 may be removed from the rod 19 by removing the screw 20.

The free end of the leaf-spring 15 is provided with a contact 21, preferably of platinum, which engages a contact-screw 22, also preferably of platinum, this screw being adjustable by means of a thumb-nut 23. A battery 24 is provided with wires 25 26, leading to binding-screws 27 and 29. Binding-screws 28 and 30 are connected by a wire 29^a.

The binding-screws 29 and 30 are mounted upon a block 31.

The post 19 is insulated from the frame 6, but is electrically connected with the binding-post 28.

A hollow casing 32 is closed by a disk 33, from which projects a stem 34 for supporting the block 31. The outer end of this stem is threaded at 34^a and is engaged by a thumb-nut 35, the arrangement being such that the thumb-nut 35 by pulling upon the rod 34 clamps the magnets 36 firmly between the disk 33 and the block 31. In order to remove the magnets, therefore, it is necessary to loosen the thumb-nut 35.

Within the casing 32 is a disk-shaped armature 37, mounted upon the end of a stem 38. A plate 39, provided with a channel 40, is secured upon a supply-pipe 41, leading to the tank or other reservoir containing the liquid fuel. This plate contains another channel 42, connected with a pipe 43, leading to the furnace for the purpose of supplying liquid fuel thereto. Within the plate is a substantially conical aperture 44, and within this aperture a valve 45 is normally free to play. A guide 46 is provided with an aperture 47, into which the stem 38 loosely projects, as indicated in the upper part of the figure. The bell-crank lever 8 is connected by means of a coil spring-wire 48 with the leaf-spring 15, and this spring is in turn supported by another leaf-spring 49, which rests loosely upon the insulation 50. The post 19 is insulated from the frame 6 by means of the insulation 51.

Normally the liquid fuel flows through the pipe 41, channel 40, casing 32, around the valve 45, through the channel 42 and pipe 43, to the fire-box. When, however, the magnet is energized and the armature 37 is drawn toward the magnet, the flow of the liquid fuel around the valve 45 is obstructed to a greater or lesser extent, and the feed of the fuel to the fire is thereby regulated. If desired, the parts can be so proportioned that the flow of the fuel is completely obstructed for the moment.

The electric circuit is as follows: battery 24, wire 25, binding-post 27, frame 6, bell-crank lever 8, screw 13, leaf-spring 15, con-

tacts 21 22, binding-post 28, wire 29^a, binding-post 30, magnets 36, binding-post 29, wire 26, and battery 24.

The operation of my device is as follows: 5 Suppose that the machinery is in operation and that the boiler 1 is carrying a normal pressure of, say, one hundred and forty pounds per square inch. Suppose, further, that the flow of the fuel is a little too free 10 and that the boiler thereby becomes heated a little above its normal temperature. The resulting increase of pressure causes the diaphragm 3 to move slightly to the left, beyond its normal position, thereby actuating the 15 bell-crank lever 8 and causing the leaf-spring 15 to bend slightly, thereby bringing the contacts 21 22 together. The battery 24 thereupon immediately energizes the magnet, which draws the armature 37, seats the valve 20 45, and checks the flow of fuel, thereby gradually checking the heat of the boiler and causing the pressure of the boiler to drop down to its normal degree.

It should be noted that the bell-crank lever 25 8 is adjustable relatively to the leaf-spring by means of the screw 13 and thumb-nut 14 and that the contact-point 22 is also adjustable relatively to the contact-point 21 upon the outer end of the leaf-spring. The bell-crank 30 lever and the leaf-spring therefore together constitute a sort of compound lever, in which great sensitiveness and great adaptability can be attained.

Having thus described my invention, I 35 claim as new and desire to secure by Letters Patent—

1. An electric regulator, comprising a boiler, a member for controlling the fuel-supply thereof, a magnet for actuating said member, 40 a pressure-motor connected with said boiler and actuated by pressure therefrom, a source of electricity, a contact connected with said magnet and with said source of electricity, said contact being normally open, and a bell-crank lever provided with an adjusting-screw 45 for engaging said contact and connected with said pressure-motor.

2. An electric regulator, comprising a boiler, a member for controlling the fuel-supply

thereof, a magnet for actuating said member, 50 a pressure-motor connected with said boiler and actuated by pressure therefrom, a source of electricity connected with said magnet, a contact connected with said magnet and with said source of electricity, means for adjusting said contact, a bell-crank lever provided with a screw for engaging said contact, means for adjusting said screw relatively to said contact, and a spring for normally compressing said lever against said pressure-motor, 60 causing said lever to be actuated thereby.

3. An electric regulator, comprising a boiler, a member for controlling the fuel-supply thereof, a magnet for actuating said member, 65 a pressure-motor connected with said boiler and actuated by pressure therefrom, a source of electricity connected with said magnet, a contact connected with said magnet and with said source of electricity, said contact being provided with a lever, a second lever connected with said pressure-motor and with said last-mentioned lever, said two levers acting together as a compound lever, thereby increasing the sensitiveness of said contact, and means for adjusting said levers relatively to 70 each other.

4. An electric regulator, comprising a boiler, a member for controlling the fuel-supply thereof, a magnet for actuating said member, 80 a pressure-motor connected with said boiler and actuated by pressure therefrom, a source of electricity connected with said magnet, a contact connected with said magnet and with said source of electricity, said contact being provided with a lever, a second lever connected with said pressure-motor and with said first-mentioned lever, thus forming a compound lever for the purpose of increasing the sensitiveness of said contact, and means for adjusting said contact relatively to said levers. 85

In testimony whereof I have signed my name to this specification in the presence of two subscribing witnesses.

CHARLES PIERSON PHILBRICK.
